UNITED STATES PATENT OFFICE.

JOSEPH H. POTTER, OF SEASIDE HEIGHTS, NEW JERSEY.

ATTACHMENT FOR JOINERS' SQUARES.

1,301,166.

Specification of Letters Patent. Patented Apr. 22, 1919.

Application filed December 29, 1916. Serial No. 139,600.

To all whom it may concern:

Be it known that I, JOSEPH H. POTTER, a citizen of the United States, residing at Seaside Heights, in the county of Ocean and

5 State of New Jersey, have invented new and useful Improvements in Attachments for Joiners' Squares, of which the following is a specification.

This invention relates to an attachment 10 for joiners' squares; and it consists in the peculiar and advantageous attachment hereinafter described and claimed.

Like characters of reference denote corresponding parts throughout the several 15 views in the drawing, in which:

Figure 1 is a plan view of an attachment constructed in accordance with the invention.

Fig. 2 is a side elevation of the same.

20 Fig. 3 is a plan view of the attachment applied to a joiner's square and showing the same positioned upon a piece of timber so that the timber can be marked and cut for use as a rafter.

25 Fig. 4 is a view similar to Fig. 3 showing the blade on the attachment adjusted so that one end of a rafter may be cut to enable the rafter to be used as a jack rafter.

Fig. 5 is a plan view of the attachment 30 removed from the joiner's square and showing the blade thereon adjusted to enable the attachment to be used as a square.

Referring now to the drawing in detail, the numeral 1 designates the body of the 35 attachment which is in the form of a rectangularly shaped bar having a top 2, bottom 3, sides 4, and ends 5, said body being formed from any suitable material of any thickness found desirable.

40 The body 1 has formed therein between its ends spaced and circular openings 6 opening out through the top 2 and bottom 3 of the body.

In each opening 6 is disposed a tube 7 45 containing a sufficient quantity of fluid to form a bubble in the tube so that the body can be used as a spirit level.

Extending longitudinally of the body 1 for a portion of its length near each end is 50 an elongated slot 8 opening out through the top 2 and bottom 3 of the body.

Through each slot 8 passes the threaded shank 9 of a screw 10, the head 11 of which is adapted to bear against the bottom 3 of the body, said shank having adjustably mounted on the portion thereof which ex-

tends beyond the top 2 of the body a wing-nut 12 which may be adjusted on the shank to contact with the top 2 of the body.

Through the above described arrangement 60 of the screws 10, it will be seen that the wing-nut 12 may be adjusted on the threaded shanks of the screws to enable the shanks of the screws to be moved longitudinally of the slots 8 and held in adjusted position 65 therein.

Slots 13 extend longitudinally of the body from each end toward the middle thereof and open out through the sides 4. Said slots are of greater length than the slots 8 70 in the body and are adapted to receive the blades 14 of the joiner's square 15 shown in Figs. 3 and 4 in the drawing.

The threaded shank 16 of a screw 17 extends above the top 2 of the body 1 near one 75 end thereof and adjacent a side 4 of the body.

A rectangularly shaped blade 18 has formed therein near one end a transversely extending opening 19 in which is loosely received the threaded shank 16 of the screw 17. 80

A wing-nut 20 is adjustably mounted on the extending portion of the shank 16 and adapted to bear on the blade 18, so that when the blade is arranged at an angle to the body 85 1 it may be held in adjusted position by means of the nut 20.

Stop members 21 and 22 are secured to the top 2 of the body 1 and arranged in such a manner that when the blade 18 is arranged 90 at a right-angle to the body, one end thereof contacts with the stop 21 and limits the turning movement of the blade in one direction.

The stop member 22 is mounted on the top 2 in such a manner that when the blade 18 is 95 arranged parallel with the body, one side edge of the blade will contact with the stop member 22 and limit the turning movement of the blade in one direction.

When it is desired to apply the attachment 100 to a joiner's square, the blades 14 of the square are positioned in the slots 13 and the wing-nuts 12 adjusted on the shanks 9 of the screws 10 to cause the body to grip the blades and retain the square connected therewith. 105

If it is desired to mark a piece of timber with the square so that the same can be cut and used as a rafter, a side 4 on the body 1 is positioned against a side of the piece of timber, so that the meeting ends of the blades of 110 the square will be positioned upon the timber as shown in Fig. 3 in the drawing.

A line is drawn on the piece of timber along one blade of the square so that when the timber is cut along the line the end of the timber may be positioned on the wall plate of a roof.

The attachment is now moved along the timber until the required length of the rafter has been reached and a line scribed on the timber along the other blade of the square.

10 When the timber has been cut along the last mentioned line, the end of the timber will fit the ridge-pole of a roof thus allowing the timber to be used as an ordinary rafter.

15 It will, of course, be understood that when the attachment has been connected with a joiner's square as described above, the attachment and square may be used to mark a piece of timber so that it may be used as a

20 stair-stringer.

If it is desired to cut the timber for use as a jack rafter, the wing-nut 20 is adjusted on the shank 16 until the blade 18 can be turned at an angle to the body 1.

25 The nut 20 is now tightened to hold the blade in adjusted position and the body 1 placed against the side of the timber to be marked.

The ends of the rafter are marked by 30 means of the blades 14 of the square 15 and the timber turned so that one end of the rafter may be marked by means of the blade 18 to correctly fit against the hip rafter when cut.

35 From the foregoing description of the attachment, it will be seen that when the same

is applied to a square, the required marks may be placed on a timber to enable the same to be cut and used as a jack rafter without the additional use of bevels, or the like. 40

When the attachment has been disconnected from a joiner's square and it is desired to use the attachment as a square, the blade 18 is adjusted to lie at right-angles to the body 1 and when in this position the attachment 45 may be used as a T-square if so desired.

Having thus described the invention, what is claimed as new, is:

An attachment for joiners' squares comprising an elongated body of greater width 50 than thickness having transversely disposed and longitudinally extending slots at opposite sides of its transverse center and closed at their ends, and also having slots extending between its opposite edges and to its ends 55 and intersecting the first named slots, headed and threaded bolts extending through the first-named slots and also through and at right angles to the second-named slots, wing nuts on said bolts, a threaded shank fixed to 60 and extending laterally from one side of the body and spaced from one of the first-named slots, a wing nut on said shank, a lateral stop on said body side, at the opposite side of the slot to said shank, and a second lateral stop 65 on said side of the body, at the opposite side of the transverse slot to the first named stop, and a marking blade pivotally mounted on said shank and arranged in different positions to bring up against said stops. 70

In testimony whereof I affix my signature.
JOSEPH H. POTTER.
